UNITED STATES PATENT OFFICE.

JOHN WOLF, OF CICERO, AND MARTIN BURGER, OF CHICAGO, ILLINOIS, ASSIGNEES, BY
MESNE ASSIGNMENTS, TO IDEAL STITCHER & MFG. CO., OF CHICAGO, ILLINOIS.

WIRE STITCHER.

Application filed September 13, 1919. Serial No. 323,658.

To all whom it may concern:

Be it known that we, JOHN WOLF and MARTIN BURGER, subjects of the Emperor of Austria, residing at Cicero, in the county of Cook and State of Illinois, and at Chicago, in the county of Cook and State of Illinois, respectively, have invented a certain new and useful Improvement in Wire Stitchers, of which the following is a full, clear, concise, and exact description, reference being had to the accompanying drawings, forming a part of this specification:

Our invention relates to wire stitchers and has to do more particularly with feed mechanism therefor, an object being to provide an improved and simplified rotary feed mechanism eliminating the objectionable reciprocating driving parts heretofore employed.

One of the features of our invention is the provision of feed mechanism having continually rotating rollers provided with a peripheral portion adapted to engage and feed the wire to a predetermined extent during the rotary movement of the feed rollers.

For a better understanding of our invention reference is to be had to the accompanying drawings in which—

Fig. 1 is a front view of the head of a well known form of wire stitcher having our improved feed mechanism applied thereto;

Fig. 2 is a sectional view along the line 2—2 of Fig. 1 through the lower feed roller and showing the check pawl mechanism;

Fig. 3 shows a portion of the face plate with the feed roller mechanism and the adjustable cap removed from the lower feed roller;

Fig. 4 is a top view of the lower feed roller showing the clearance on the periphery thereof; and

Fig. 5 is a detail view of the feed pawl.

Referring now more in detail to our invention as shown herein, it is illustrated in connection with a well known form of wire stitcher comprising a face plate 10 carrying a cam 11 connected by means of a link 12 to a driver 13 and by means of a roller 14 to a former 15. The former and driver are supported in a box 16 and cooperate with an anvil 17 which is supported in a well known way so as to reciprocate forwardly and backwardly. A cutter box 18 is adjustably supported by the face plate 10, being movable by means of a hand wheel 19 in a well

known manner. A wire guide 20 is also carried by the cutter box 18 through which the wire 21 is fed.

Now as to the feed mechanism, this comprises preferably a pair of feed rollers consisting of an upper straight faced feed roll 22 and a lower feed roll 23, said rollers being connected by gears 24, 25, the driving power coming from the main shaft through gears 26, 27 and 28, gear 27 acting as an idler and gear 28 being supported upon the main shaft 29. The gear ratio is preferably such that for each complete reciprocation of the former and driver, one revolution of the feed rollers is effected, although, of course, it will be apparent that other proportions may be employed if desired.

In order to effect an intermittent feeding of the wire 21 we preferably provide a yielding feed pawl 30 pivotally supported upon a pin 31 carried by the lower feed roll 23. A spring 32 acts to press the feed pawl 30 outwardly but its movement is limited by engagement with the feed roller 23 at point 23^a. This feed pawl 30 is preferably so adjusted that its feed surface during the feeding portion of the revolution, presses the wire 21 into intimate contact with the upper feed roller 22, the combined rotation of the two thus feeding the wire 21 into the stapling mechanism. Roll 23 has its peripheral face cut away at 23^b to insure clearing the wire during the non-feeding period.

In the form of our invention as illustrated herein we employ a feed pawl 30 having a feed face of a length sufficient to feed wire long enough for the largest staple and then provide adjustable feed control means so that the length of wire fed may be varied according to the size of a staple wanted. To this end we provide a sizing roller 33 supported upon a plate 34 adjustably carried upon the front end of the lower feed roll shaft 35, the said plate 34 being locked by means of a nut 36 threaded upon the shaft 35 but permitting free rotation of feed roll 23. This plate 34 may thus be rotatably adjusted upon the shaft 35 thereby moving the sizing roller 33 to the right or left. During the rotation of the lower feed roller 23 the feed pawl 30 passes into contact with the sizing roller 33 and as the rear edge 30^a of the feed pawl 30 leaves the sizing-roller

33, the feed pawl is permitted to snap outwardly and engage the wire 21 so as to start the feeding operation thereof. That is, so long as the feed pawl 30 is rotating in engagement with the sizing roller 33, its feed face is held feed-clear of the wire 21. But as soon as it clears the sizing-roller 33 it snaps into feeding engagement with the wire 21 by pressing it against the opposite roller 22. It will thus be apparent that although a single feed pawl 30 is employed, by means of the adjustable sizing roller 33 the release of pawl 30 may be varied so as to feed various lengths of wire 21. It will, of course, be readily seen that although we provide an adjustable feed pawl 30, we may also use a plurality of different sizes of feed pawls whose feeding surfaces are according to the different lengths of the wire to be fed. Thus the size of the staple is determined by the length of the feed face on the feed pawl 30 instead of by the time of release as illustrated herein.

In order to securely hold the wire during the operation of the machine we also provide the usual check pawl 38, guide and wire straightener 39, the form shown being well known.

Now as to the operation, the cutter box 30 is adjusted relative to the anvil 17 and former 15 by means of the hand wheel 19 in a well known manner so as to secure a balanced staple, that is a staple having equal legs, this being done during the adjusting operation either before or after the proper feed length has been determined.

The sizing-roller 33 is also adjusted by loosening the lock nut 36 and moving the plate 34 so that the rear edge 30^a of the feed pawl will free itself from the sizing roller 33 to press the wire 21 against the opposite feed roller 22 at the proper time. The lock nut is then tightened up again. Thus by means of the connecting gears 24, 25, 26, 27, 45 and 28, feed rollers 22 and 23 are given one revolution for each complete reciprocation of the stapling mechanism, and although the feed rollers 22-23 are rotating continually during the operation of the stitcher, feeding contact between the two feed rollers 22-23 and the wire 21 is not effected except during the time the feed pawl 30 is pressing the wire 21 against the opposite feed roll 22. The length of this feeding operation is, of course, determined by the adjustment of the sizing roller 33. Thus any size staple may be fed within the limit of operation of the machine.

The driving mechanism for the stitcher is not shown but this may be applied as desired, the machine shown being driven from the main shaft 29 which usually extends rearwardly and carries a pulley and clutch controlled from a foot treadle at the base of the stand ordinarily provided. It will, of course, be understood that the usual clinch-

ers and table are provided beneath the head but this has not been shown as their operation is well understood.

Although in illustrating our invention we have chosen a preferred form we do not desire to be limited to the matter shown and described as changes and modifications will readily occur to those skilled in the art and we aim to cover all such changes and modifications as come within the spirit and scope of the appended claims.

What we claim as new and desire to secure by Letters Patent is:

1. In a wire stitcher, wire feed mechanism comprising a pair of continually rotating feed rollers having opposed peripheral feed edges between which the wire is fed, with means for effecting an intermittent feeding of the wire by said rollers, said means including a metallic yieldingly mounted peripheral edge of one of the rollers.

2. In a wire stitcher, wire feed mechanism comprising a pair of continually rotating feed rollers having opposed peripheral feed edges between which the wire is fed, with means for effecting an intermittent feeding of the wire by said rollers, said rollers being mounted upon relatively fixed shafts, and relatively stationary means mounted independent of the rollers and acting upon the rollers for varying the feeding period.

3. In a wire stitcher, wire feed mechanism comprising a pair of continually rotating feed rollers having opposed peripheral feed edges between which the wire is fed, with means for effecting an intermittent feeding of the wire by said rollers, said means including a yielding peripheral edge of one of the rollers, and means for varying the feeding period.

4. A wire feed roller for wire stitchers having a yieldingly mounted metallic feed section for yieldingly engaging the wire with a peripheral feeding surface the feed engaging length of which determines the amount of wire fed.

5. Feed mechanism for wire stitchers comprising a feed roller having a yieldingly mounted metallic feed section, and means for varying the feeding period of the feed section.

6. Feed mechanism for wire stitchers comprising a continually rotating fixed axis feed roller having a peripheral feeding edge, and relatively stationary means mounted independent of the roller and co-operative therewith for varying the feeding period of the feed roller.

7. Feed mechanism for wire stitchers comprising a continually rotating feed roller, and an automatically controlled metallic feed pawl carried by the roller for effecting an intermittent feed.

8. Feed mechanism for wire stitchers comprising a pair of continually rotating relatively fixed axis opposed rollers provided with peripheral feed edges, and means cooperative with the rollers for effecting feeding contact of the rollers during a portion of each revolution. 30
9. A wire stitcher comprising driving mechanism including a rotatable driving shaft, and feed mechanism including a pair of feed rollers, driving means connecting the rotatable shaft to the feed rollers for effecting a continual constant rotation thereof, a metallic feed pawl carried by one of the rollers, and a relatively stationary adjustable stop for varying the feeding period of the feed pawl. 35
10. A wire stitcher comprising driving mechanism including a rotatable driving shaft, and feed mechanism including a pair of feed rollers, driving means connecting the rotatable shaft to the feed rollers for effecting a continual constant rotation thereof, a pivoted peripheral edge portion carried by one of the rollers, and a relatively stationary adjustable stop for varying the feeding period of the pivoted peripheral edge portion. 40
11. In a wire stitcher, a wire feed mechanism including a pair of connected continuously rotatable feed rollers having contiguous peripheral edges between which the wire is fed, one of said rollers having a peripheral section movably mounted in a cut-away portion of the roller, and a spring for pressing said section outwardly so as to press the wire into intimate contact with the peripheral edge of the other roller so as to feed the same. 45
12. In a wire stitcher, a wire feed mechanism including a pair of connected continuously rotatable feed rollers having contiguous peripheral edges between which the wire is fed, one of said rollers having a peripheral section movably mounted in a cut-away portion of the roller, and a spring for pressing said section outwardly so as to press the wire into intimate contact with the peripheral edge of the other roller so as to feed the same, and a circularly adjustable stop mounted stationary relative to the section-roller for determining the wire feeding period thereof. 50

In witness whereof, we hereunto subscribe our names this 30th day of July, A. D., 1919.

JOHN WOLF.
MARTIN BURGER.
